[57] CLAIM

The ornamental design for a coin separator assembly, as
shown.

DESCRIPTION

FIG. 1 is a front elevational view of a coin separator
assembly showing my new design;

FIG. 2 is an end elevational view thereof;

FIG. 3 is a side elevational view thereof;

FIG. 4 is a rear elevational view thereof;

FIG. 5 is an elevational view of the side opposite that
shown in FIG. 3; and

FIG. 6 is an elevational view of the side opposite that
shown in FIG. 2.
